UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,426,817.

Specification of Letters Patent. Patented Aug. 22, 1922.

Application filed December 11, 1919. Serial No. 344,095.

To all whom it may concern:

Be it known that I, EDGAR H. CLARK, a citizen of the United States, residing at Richmond Hill, in the county of Queens, 5 State of New York, have invented certain new and useful Improvements in Telephone-Exchange Systems, of which the following is a full, clear, concise, and exact description.

10 This invention relates to telephone exchange systems of the semi-automatic type, and more particularly to the type employing a B operator for extending a connection semi-automatically from an originating 15 operator's position to a terminating operator's position over a two conductor trunk.

The object of the invention is the provision of means permanently bridged across the two conductors of an interoffice trunk 20 for holding the trunk busy at its outgoing end until after the trunk is released at its incoming end.

A further object of the invention is the provision of means under the control of the 25 terminating operator and operable over the two conductors of an interoffice trunk terminating in such operator's position for making such trunk busy at will to calls outgoing from the originating office.

30 The main feature of the invention resides in the provision of a high resistance relay permanently bridged across the two conductors of the trunk circuit extending between two offices, which because of its high re-

35 sistance does not energize during the building up and continuance of a connection over the trunk circuit and does not therefore interfere with the normal functioning of the system, but which energizes upon release of

40 the trunk circuit at the outgoing end to place a busy potential upon the test terminal of the trunk appearing in the banks of all office switches at the originating office having access thereto. This busy condition is

45 maintained until the terminating operator pulls down the connection at her position. While the primary function of this holding relay is as above described to hold the inter- 100 office trunk busy until the terminating oper-

50 ator pulls down the connection, the relay may also be employed to place an artificial busy condition on the outgoing terminals of the trunk at the will of the terminating operator.

55 These and other features of the invention

will become more apparent as the description progresses. Reference will now be made to the accompanying drawing which shows only so much of the circuit and apparatus associated with the positions of an originating operator O, a B operator O', and a terminating operator O'' as is necessary for an understanding of the invention, together with a subscriber's line C terminating before the position O'' of the terminating operator.

The circuits of this system are designed to be employed in connection with the corresponding circuits disclosed in the co-pending application of Alben E. Lundell and 70 Edgar H. Clark Serial No. 199,886, filed November 2, 1917, Patent 1,342,823, June 8, 1920. Inasmuch as the invention involves only a portion of the apparatus of the B operator's position and terminating operator's position, it is not deemed necessary to 75 an understanding of the invention to show the entire circuits necessary for extending a connection from the line of a calling subscriber to and through the circuits at the 80 terminating operator's position to the line of the desired subscriber, and therefore only so much of the circuits as are required to fully disclose the novel features of this invention have been disclosed.

85 The manner in which the circuits are organized will best be presented in connection with a description of the mode of their operation. It will be assumed that an originating operator at position O has seized 90 the trunk line shown in the drawing terminating in the B operator's position O', and that in response to the instructions of the originating operator the B operator has set the impulse controlling registers of her 95 position for selecting a trunk outgoing from such position and terminating in a plug ended cord circuit at an outlying office in which the line of the desired office terminates, and for setting the number indicating register at the terminating office to register the designation of the desired line before the terminating operator by means of apparatus shown more in detail in said application hereinbefore referred to.

105 The association of the calling plug (not shown) of the originating operator's cord circuit with the trunk jack J, has, in the well known manner, caused the energization of sleeve relay 2 which at its armature and 110

front contact connects the polarized supervisory relay 3 across the trunk conductors 4 and 5 extending to the position O' to the B operator. In response to the seizure of the 5 trunk circuit 4, 5, the B operator sets the registers of the register sender at her position in accordance with the designation of the desired line which is communicated to her by the originating operator, which register sender then proceeds in the well known 10 manner to set the brushes 6, 7 and 8 of the office selector upon the terminals of an idle trunk circuit leading to the office in which the desired line is located. Following the 15 setting of the office selector, the sequence switch associated with the office selector moves its cam springs 9 and 10 into position 11 in which position the impulse sender at the B operator's position is associated with the conductors 11 and 12 of the 20 interoffice trunk in readiness for the transmission of impulses over the trunk for setting the call indicator at the terminating operator's position O'.

25 Upon the establishment of the circuit over the interoffice trunk, relays 13 and 14 become energized. The circuit of these relays may be traced from grounded battery through the right-hand winding of relay 14 at the B operator's position, through the lower contact of sequence switch spring 15 (14) of the sender sequence switch of the B operator's position, through the lower contact of sequence switch spring 10 (11), over brush 30 7 of the office selector, trunk conductor 12, the lower armature and back contact of relay 16, the inner normally closed armature contacts of reversing relay 17, the left-hand winding of relay 13, the outer left-hand armature and back contact of relay 18, the 35 back contact and inner left-hand armature of relay 18, the right-hand winding of relay 13, the outer normally closed armature contacts of reversing relay 17, the upper armature and back contact of relay 16, trunk conductor 11, brush 6 of the office selector, lower contact of sequence switch spring 9 (11), the lower contact of the sender sequence switch spring 19 (14), and thence to ground 40 through the left-hand winding of relay 14. Relay 13 energizes in this circuit and establishes a circuit for the slow acting relay 20, which may be traced from grounded battery through the winding of this relay and thence to ground through front contact and left-hand armature of relay 13. Relay 20 upon energizing establishes at its armature and front contact, a locking circuit for itself extending through its winding and 45 through the back contact and armature of sleeve relay 21 and thence to ground through the left-hand winding of relay 18. Relay 18 does not energize at this time however, since its winding is short-circuited at the left-hand armature and front contact of relay 13. At 50

the time relay 13 energized, in the circuits previously traced over the interoffice trunk, relay 14 at the B operator's position energized, closing at its armature and front contact a circuit for driving the sender sequence 55 switch 22 out of position 14 and into position 16, this circuit extending from grounded battery through the magnet winding of the sequence switch, the front contact and armature of relay 14 and thence to ground 75 through the contact of sequence switch spring 23.

Sequence switch 22 upon leaving position 14 disconnects relay 14 from the trunk circuit and connects the relay 24 to the trunk 80 circuit, through the upper contacts of sequence switch springs 15 and 19. Since now battery potential at the windings of relay 14 has been disconnected from the trunk, the energizing circuit of relay 13 at the terminating office is destroyed and relay 13 thereupon deenergizes, opening at its left-hand armature and front contact the shunt circuit which has prevented the energization of relay 18. Relay 18 thereupon energizes closing at its right-hand armature and front contact a locking circuit extending through its right-hand winding and to ground over the conductor 25 which extends to the holding circuit of the terminating operator's call 95 indicator as fully disclosed in the application hereinbefore referred to. At its left-hand armatures and back contacts relay 18 disconnects the metallic loop which was normally connected across the windings of relay 100 13 and at these armatures and front contacts connects grounded battery and ground respectively to the right-hand and left-hand windings of relay 13. Relay 13 re-energizes and at its armature and front contact establishes a circuit for the relay 26 which circuit may be traced from grounded battery through the winding of this relay and thence to ground at the front contact and left-hand armature of relay 13. 110

The energization of relay 26 establishes a circuit for the assignment lamp 27, which circuit may be traced from grounded battery through the assignment lamp, through the outer right-hand armature and back contact 115 of the assignment relay 44, through the inner left-hand armature and back contact of relay 28 and thence to ground through the front contact and armature of relay 26. The terminating operator upon noting the illumination of the assignment lamp 27 depresses the assignment key K individual to the trunk circuit which has been taken for use, thereby closing a circuit for the assignment relay 44 and for the holding relay of 120 the call indicator (not shown) associated with her position, which circuit may be traced from ground through the contacts of the assignment key K, the right-hand winding of relay 44, the back contact and outer 125 130

left-hand armature of relay 28, thence over the conductor 29, through the holding relay of the call indicator and to grounded battery. Relay 44 energizes in this circuit and 5 at its left-hand armature and front contact establishes a holding circuit for itself independent of the contacts of the assignment key, which circuit may be traced from ground, through the left-hand armature and 10 front contact, thence through both windings of relay 44 and to grounded battery over the circuit previously traced. At its outer right-hand armature and back contact, assignment relay 44 opens the circuit of the assignment 15 lamp 27 causing this lamp to become extinguished and at its inner right-hand armature and front contact closes a circuit for the relay 16 which may be traced from grounded battery through the inner right-hand armature and front contact of relay 44 and 20 thence to ground through the winding of relay 16.

The energization of relay 16 disconnects the interoffice trunk conductors 11 and 12 25 from the windings of relay 13, and connects these trunk conductors to the impulse conductors 30 and 31 extending to the call indicator at the terminating operator's position. The extension of the trunk circuit to these 30 impulse conductors causes, in the manner set forth in the application hereinbefore referred to, the operation of the sending mechanism at the B operator's position to send impulses to the call indicator at the terminating operator's position in accordance with 35 the setting of the registers at the B operator's position for setting up the designation of the desired subscriber upon the call indicator at the terminating operator's position. 40 The terminating operator upon noting the designation of the desired line upon the lamps of the call indicator takes up the plug P' in which the selected trunk circuit terminates and, after making the usual test of 45 the jack of the desired line to determine the busy or idle condition of this line, inserts the plug in the jack J'. A circuit is now established through the cut-off relay 32 of the called line over the sleeve terminals of 50 the plug and jack through the winding of the sleeve relay 21 and thence to grounded battery through the winding of relay 28. The energization of sleeve relay 21 disconnects at its upper armature and back contact 55 the connection between the tip of the plug and the test conductor leading to the operator's headset, and at its armature and front contact extends a connection from the tip of the plug to the upper right-hand winding of 60 the repeating coil 33. At its lower armature and back contact, sleeve relay 21 opens the initial energizing circuit of relay 18 and closes a new energizing circuit for relay 18 extending from grounded battery through 65 the front contact and lower armature of re-

lay 21 and thence to ground, through the left-hand winding of relay 18. This circuit maintains the relay 18 energized until the connection is taken down upon the termination of the conversation. Relay 28 which is 70 also energized in series with the sleeve relay 21 opens at its outer left-hand armature and back contact the locking circuit of the assignment relay 44, which relay thereupon deenergizes, opening the circuit for relay 16 75 which in turn disconnects the impulse conductors 30 and 31 from the trunk conductors 11 and 12 and reconnects the relay 13 to these trunk conductors. Relay 13 which deenergized at the time relay 16 was energized now 80 reenergizes relay 26 and maintains this relay energized until the release of the inter-office trunk circuit at the originating office. At its inner left-hand armature and back contact, relay 28 further opens the circuit of 85 the assignment lamp 27 for preventing further illumination of this lamp.

At its right-hand armature and front contact, relay 28 establishes a circuit for initiating the application of ringing current to 90 the line of the desired subscriber. This circuit may be traced from grounded battery through the disconnect lamp 34, through the right-hand armature and front contact of relay 28, the back contact and armature of 95 ringing cut-off relay 35, the back contact and left-hand armature of relay 36 and thence to ground through the winding of ringing relay 37. Ringing relay 37 energizes in this circuit but the resistance of 100 this relay is sufficient to prevent the illumination of lamp 34. At its armatures and front contacts, relay 37 connects a source of ringing current to the line of the called subscriber, the circuit over which the ringing current flows extending from the source of ringing current, through the winding of the ringing cut-off relay 35, through the front contact and lower armature of ringing relay 37, over the ring contacts of the 110 plug and jack, over one limb of the called subscriber's line, through the ringer 38 and condenser 39 at the substation of the called subscriber's line, thence back over the other limb of the subscriber's line, through the tip 115 contacts of the jack and plug, the front contact and upper armature of sleeve relay 21 and thence to ground through the upper armature and front contact of ringing relay 37.

The called subscriber upon responding to the call removes his receiver from its switchhook thereby reducing the resistance of the circuit just traced, causing the energization of the ringing cut-off relay 35 in the well 120 known manner. The energization of this relay opens at its armature and back contact the shunt which heretofore extended around the winding of relay 36. Relay 36 now energizes in series with the ringing relay 37 125 130

and at its left-hand armature and front contact establishes a locking circuit for itself extending from its winding to grounded battery through the front contact and right-hand armature of relay 28. The connection of this locking ground to the winding of relay 36 places a shunt around the winding of the ringing relay 37 thereby causing the deenergization of relay 37. The deenergization of relay 37 disconnects at its armatures and front contacts the source of ringing current and ground from the tip and ring contacts of the plug, and at its armatures and back contacts connects the tip and ring contacts of the plug to the right-hand windings of the repeating coil 33. The calling supervisory relay 40 now energizes in a circuit extending over the called subscriber's line, which may be traced from grounded battery through the lower right-hand winding of the repeating coil 33, the winding of the calling supervisory relay 40, back contact and lower armature of relay 37, the ring contacts of the plug and jack, over the subscriber's line loop, over the tip contacts of the plug and jack, the front contact and upper armature of sleeve relay 21, the upper armature and back contact of relay 37 and thence to ground through the upper right-hand winding of repeating coil 33. The energization of supervisory relay 40 and relay 36 establishes a circuit for the reversing relay 17 which may be traced from grounded battery through the winding of relay 17, armature and front contact of supervisory relay 40 and thence to ground through the right-hand armature and front contact of relay 36.

The energization of reversing relay 17 causes the reversal of the battery leads extending through the windings of relay 13 and thereby causes a reversal in the direction of the current flowing over the inter-office trunk and through the windings of the polarized supervisory relay 3 at the originating operator's position. This supervisory circuit may be traced from grounded battery through the front contact and inner left-hand armature of relay 18, the right-hand winding of relay 13, the make-contacts of the outer right-hand armature of relay 17, the lower left-hand winding of repeating coil 33, the back contact and lower armature of relay 16, the trunk conductor 12, brush 7 of the office selector, the upper contact of sequence switch spring 10 (12), the sequence switch of the office selector having moved into position 12 following the setting of the call indicator at the terminating operator's position, trunk conductor 5 through the lower right-hand winding of repeating coil 41, the armature and front contact of sleeve relay 2, the windings of the polarized supervisory relay 3, the upper right-hand winding of repeating coil 41,

trunk conductor 4, the upper contact of sequence switch spring 9 (12), the brush 6 of the office selector, trunk conductor 11, the upper armature and back contact of relay 16, the upper left-hand winding of repeating coil 33, the make-contacts of the inner armature of relay 17, the left-hand winding of relay 13, and thence to ground through the outer left-hand armature and front contact of relay 18. The polarized supervisory relay 3 energizes in such a manner as to signal the originating operator that the called subscriber at the terminating operator's position has responded to the call.

During the establishment of the connection, the high resistance relay 42 has been bridged across the conductors 11 and 12 of the interoffice trunk circuit at the outgoing end of the trunk circuit, but due to its high resistance and to the comparatively low resistance of the windings of relays 13, 14 and 3, relay 42 has not diverted sufficient current through its own winding to interfere with the proper functioning of the other relays above mentioned which have been connected across the trunk circuit at various stages in the establishment of the connection, and the relay 42 has not received sufficient current to cause its own energization. Upon the termination of the conversation, and the restoration of the receiver to its switchhook at substation C of the called line, the calling supervisory relay 40 becomes deenergized and thereby opens the circuit of the reversing relay 17, which in turn deenergizes and again reverses the connection of the battery leads to the conductors 11 and 12 of the interoffice trunk circuit. The reversal in the direction of current flow over the trunk circuit causes the polarized supervisory relay 3 at the originating office to be energized in such a manner as to give the originating operator an indication that the called subscriber at the terminating office has released. The originating operator thereupon removes the calling plug of her cord circuit from the jack J thereby opening the circuit of sleeve relay 2. The circuit previously traced extending through the windings of the polarized relay 3 and the windings of relay 13 at the terminating office, is now opened at the armature contacts of sleeve relay 2, and relay 13 is thereby deenergized, opening at its armature and front contact the circuit of relay 26. Relay 26 thereupon deenergizes, closing at its armature and back contact a circuit for the disconnect lamp 34. The circuit of lamp 34 may be traced from grounded battery through this lamp, the right-hand armature and front contact of relay 28 and thence to ground at the back contact and armature of relay 26.

Upon the opening of the trunk circuit at the contacts of sleeve relay 2, the low re-

sistance bridge extending across the inter-office trunk through the windings of supervisory relay 3 is removed from around the winding of the high resistance relay 42, and this relay thereupon receives sufficient current through the windings of relay 13 to cause its energization. Relay 13 however, does not remain energized in series with relay 42. Relay 42 at its armature and front contact connects ground to the multiple test terminals 43 appearing in the banks of all office selectors which have access to the trunk 11, 12 for the purpose of making this trunk circuit busy until the terminating operator has released the trunk at the terminating office. At the time the originating operator pulled down the connection with the interoffice trunk at her position, the apparatus at the originating office and B operator's position which was utilized in establishing the connection with the inter-office trunk was restored to normal position in the well known manner.

The terminating operator upon noting the illumination of the disconnect lamp 34 removes the plug P' from the jack J' causing thereby the deenergization of sleeve relay 21 and of relay 28. The deenergization of relay 28 opens the circuit of the disconnect lamp 34, and at its left-hand armatures and back contacts restores the circuits of the assignment relay 44 and the assignment lamp 27. The deenergization of sleeve relay 21 opens the locking circuit of relay 18 which thereupon deenergizes opening at its left-hand armatures and front contacts the circuit which extends through the winding of the high resistance relay 42. This relay thereupon deenergizes removing the busy potential from the multiple terminals 43 and freeing the interoffice trunk for further use.

Should the terminating operator at any time desire to make any of the interoffice trunks, terminating in her position, artificially busy, it is only necessary for her to insert the terminating plugs of such trunk circuits in make-busy-jacks. Assuming that the operator desires to make the trunk shown in the drawing artificially busy, she inserts the plug P' in make-busy-contact similar to the jack J', thereby causing the energization of sleeve relay 21 in the manner hereinbefore set forth. This relay at its lower armature and front contact establishes a circuit through the left-hand winding of relay 18 which in turn at its left-hand armatures and front contacts, connects grounded battery and ground through the windings of relay 13 to the trunk conductors 11 and 12. The high resistance relay 42 energizes in this circuit, and at its armature and front contact places a busy ground potential upon the multiple terminals of the trunk to prevent seizure of this

trunk by an office selector at the originating office.

It is apparent from the foregoing description that the employment of a high resistance relay bridged across the conductors of a two conductor interoffice trunk is particularly advantageous since the trunk may be made busy without the employment of additional cable conductors and without interfering in any way with the normal functioning of the system.

What is claimed is:

1. In a telephone exchange system, an originating office, a terminating office, a two conductor trunk circuit extending between said offices, a high resistance relay permanently bridged across said circuit at the outgoing end thereof, means under the control of said relay for placing a busy potential upon the outgoing terminals of said circuit, and means at the terminating office for causing the operation of said relay.

2. In a telephone exchange system, an originating office, a terminating office, a two conductor trunk circuit extending between said offices, a high resistance relay permanently bridged across said circuit at the outgoing end thereof, means under the control of said relay for placing a busy potential upon the outgoing terminals of said circuit, and means at the terminating office for causing the operation of said relay upon disconnection from the terminals of said trunk circuit at the originating office.

3. In a telephone exchange system, an originating office, a terminating office, a two conductor trunk circuit extending between said offices, a high resistance relay permanently bridged across said circuit at the outgoing end thereof, means under the control of said relay for placing a busy potential upon the outgoing terminals of said circuit, and means at the terminating office for causing the operation of said relay upon disconnection from the terminals of said trunk circuit at the originating office, and for maintaining the energization of said relay until the release of the circuit at the terminating office.

4. In a telephone exchange system, an originating office, a terminating office, a two conductor trunk circuit extending between said offices and terminating at the latter office in a connection plug, a high resistance relay permanently bridged across said circuit at the outgoing end thereof, means under the control of said relay for placing a busy potential upon the outgoing terminals of said circuit, and means at the terminating office under the control of said connection plug for causing the operation of said relay upon disconnection from the terminals of said trunk circuit at the originating office.

5. In a telephone exchange system, an

6
originating office, a terminating office, a two conductor trunk circuit extending between said offices, a high resistance relay permanently bridged across said circuit at the outgoing end thereof, means under the control of said relay for placing a busy potential upon the outgoing terminals of said circuit, low resistance operating bridges normally connected across said circuit for enabling an extension of a connection over said circuit, said bridges rendering said relay inoperative, and means at the terminating office for causing the operation of said relay upon the disconnection of said low resistance bridges from said circuit.

5
10
15
20
25
30
6. In a telephone exchange system, an originating office, a terminating office, a two conductor trunk circuit extending between said offices and terminating at the latter office in a connection plug, a high resistance relay permanently bridged across said circuit at the outgoing end thereof, means under the control of said relay for placing a busy potential upon the outgoing terminals of said circuit, low resistance operating bridges normally connected across said circuit for enabling an extension of a connection over said circuit, said bridges rendering said relay inoperative, and means under the control of said connection plug for causing the operation of said relay upon the disconnection of said low resistance bridges from said circuit.

7. In a telephone exchange system, an originating office, a terminating office, subscribers' lines terminating in said latter office, a two conductor trunk circuit extending between said offices and terminating at the latter office in a connection plug, a high resistance relay permanently bridged across said circuit at the outgoing end thereof, means under the control of said relay for placing a busy potential upon the outgoing terminals of said circuit, low resistance operating bridges normally connected across said circuit for enabling the extension of a connection over said circuit, said bridges rendering said relay inoperative, means for causing the operation of said relay upon the disconnection of said low resistance bridges from said circuit, and means for deenergizing said relay upon removal of said plug from the jack of the called subscriber's line.

8. In a telephone exchange system, an originating office, a terminating office, a plurality of two conductor trunk circuits extending between said offices, high resistance relays permanently bridged across said circuits at the outgoing ends thereof, and means at the terminating office for causing the operation of said relays at will to render any or all of said circuits artificially busy.

In witness whereof, I hereunto subscribe my name this 5th day of December A. D., 1919.

EDGAR H. CLARK.
